No. 853,067.

PATENTED MAY 7, 1907.

J. M. DAVIES.

SOAP HOLDER.

APPLICATION FILED APR. 12, 1906.

UNITED STATES PATENT OFFICE.

JOHN M. DAVIES, OF PLATTSBURG, NEW YORK.

SOAP-HOLDER.

No. 853,067.

Specification of Letters Patent.

Patented May 7, 1907.

Application filed April 12, 1906. Serial No. 311,267.

To all whom it may concern:

Be it known that I, JOHN M. DAVIES, residing at Plattsburg, in the county of Clinton and State of New York, have invented a new and Improved Soap-Holder, of which the following is a specification.

My invention relates to improvements in that class of devices or means for pendently supporting a cake or bar of soap in convenient proximity to wash basins or bowls of bath rooms, laboratories and similar compartments in dwellings, railway stations and other public and private places, and it primarily seeks to provide a soap-holding means of the character stated, of a simple, ornamental, and economical construction, in which the soap is especially positioned so that when grasped for use, it is held directly over the wash bowl or basin and when released it is automatically returned to its position adjacent the back end of the bowl or wash basin.

In its generic nature, my invention comprehends an improved construction of stand or holder, more especially designed for use on the modern types of wash basins or bowls and a means adapted for convenient connection with the water faucets of a wash stand for sustaining the said holder at its operative position.

In its more complete nature, my invention includes a special construction of holder including a flexible suspension member for the soap and an improved means that detachably connects with the lower end of the said suspension member for supporting the soap cake or bar, and in which the use of springs and similar devices commonly employed in washstand soap holders is entirely dispensed with.

In its still more subordinate features, my invention consists in certain details of construction and peculiar combination of parts, all of which will be hereinafter fully described, pointed out in the appended claims and illustrated in the accompanying drawings, in which:—

Figure 1, is a perspective view of a wash stand with my improved soap holder in its operative position. Fig. 2, is a vertical section of the same, the devices together with the soap cake being in their normal position. Fig. 3, is a similar view showing the soap cake drawn out for use, Fig. 4, is a horizontal section on the line 4—4 of Fig. 2. Fig. 5, is a detail view of the bent wire bracket for sustaining the holder in its operative position.

Fig. 6, is a detail perspective view of the weight. Fig. 7, is a view of a preferred form of soap cake used in connection with my invention.

In its practical arrangement, my soap holding means comprises a light metallic frame 1 of suitable height, having a vertical compartment 2 extended its full height open at the top and bottom, the latter being flat so as to aid in properly supporting the holder on the wash stand or basin, and to provide for fastening the same in position, especially on the modern marble top stands or bowls, the holder is held by a bent bracket 3 formed of a twisted strand of stout wire, the loop end of which is bent into a hook 4 adapted to engage the eye 5 in the upper end of the holder whereby the said holder can be readily slipped on or off the bracket.

From the loop or hook end the bracket is stiffened by twisting the two strand members as at 6, and one of the said members is continued in a substantially horizontal direction as at 7 and terminates with a spring loop 80 adapted to slip over and clamp against the upper part of the faucet above the valve chamber and the other member is bent downwardly at an angle to form a brace 8, the end of which terminates in a U-shaped 85 hook, adapted to slip over and clamp upon the faucet below the valve chamber therein, as clearly shown in Fig. 7.

At the lower end, the holder has its front wall extended laterally at each side as at 10 90 to form a splash board, and the said front side above the splash board is preferably inclined rearwardly and provided with a pocket 11 for holding tooth brushes and other bath room accessories.

12 designates a pulley mounted in the upper end of the holder, over which takes a flexible suspension means, chain, wire or catgut, to one end of which is connected the bar or cake of soap in the manner presently explained and to the other end of which is attached a flat weight 13, movable in the vertical chamber X of the holder and of substantially the width and length of said chamber and to provide for the proper guiding of the said weight as it is moved up or down, the opposite ends of the weight have tongues 14 that fit in the vertical slots 15 in the side of the holder as clearly shown in the drawings.

16 designates a removable plate adapted to be laid upon the weight member 13, said plate having a slot 17 in one edge whereby it

can be readily slipped edgewise over the pulley 12 and the weight chain or cord. This plate, which may be used in connection with the weight 13 to counterbalance the weight 5 of the soap at the start, may be removed when the soap has been used and its weight materially diminished, by pulling the weights to the open top of the holder.

By contracting the rear portion of the 10 holder to form a guide for the counter-weight, and projecting the upper part of the holder forward, there is provided a supplemental bottom portion 27 slotted at 28 for the passage of the flexible soap holding member, 15 which passage at the front end is made with a curved guard 29 to prevent cutting the cat-gut or tearing out the front end of the bottom member 27 and furthermore, such arrangement of parts provides for a recess or 20 space to receive the soap when at its normal position and for the more effectively catching the splashings against the splash board portion of the holder.

From the foregoing, taken in connection 25 with the drawings, the advantages and the manner in which my invention can be utilized will be readily understood.

Since the ordinary soap cakes are difficult to penetrate with the holding pin 22, I prefer 30 to use a soap cake formed with a longitudinal opening 22^a, as shown in Fig. 9.

Having thus described my invention, what I claim and desire to secure by Letters Patent, is:—

35 1. The combination with the holder, an extensible means on the holder for pendently sustaining a bar or cake of soap, means for

securing the holder on the wash stand or basin, said holder including a splash board portion against which the soap bar or cake rests 40 when at its normal position.

2. The combination with a holder having a contracted vertical chamber at its lower end, an outwardly projected front portion above the contracted vertical chamber, and a splash 45 board portion below the said projected front portion against which the soap bar or cake rests when at its normal position, means for supporting the holder on the wash stand or basin, and a means mounted on the holder, 50 comprising a supporting pulley, a flexible member that takes over the pulley and extended down over the splash board portion a means at one end of the flexible member for attaching the soap body and a counter-poise 55 on the other end of the flexible member movable and guided in the contracted vertical chamber of the holder, as set forth.

3. The combination with the holder having vertical alining slots in the opposite ends, 60 a guide pulley in the upper end, a counterpoise movable in the holder having lateral tongues engaging the slots, a supplemental counterpoise removably mounted on the main counterpoise, a flexible member 65 connected to the main counterpoise passing over the guide pulley and means for engaging with the lower end of said flexible member for sustaining a cake or bar of soap thereon.

JOHN M. DAVIES.
